UNITED STATES PATENT OFFICE.

FLOYD S. MUCKEY, OF NEW YORK, N. Y., ASSIGNOR, BY DIRECT AND MESNE ASSIGNMENTS, OF ONE-TENTH TO JOSEPH F. O'BRIEN, OF WEST NEW YORK, NEW JERSEY; THREE-TENTHS TO JOSEPH W. GOODWIN, OF RICHMOND HILL, NEW YORK; AND SIX-TENTHS TO MUCKEY PATENTS CORPORATION, A CORPORATION OF NEW YORK.

PIANO.

Application filed April 15, 1919. Serial No. 290,189.

This invention relates to improvements in pianos.

There are three prerequisites to obtaining the best tone quality in any musical instrument, namely: (1) the fundamental of each composite tone produced should at all times have greater intensity than any other partial tone of the composite tone, (2) the partial tones of each composite tone should gradually diminish in intensity as they rise in series from the fundamental, and (3) all the partial tones of each composite tone should continue without any intermittence and with the same relative intensity to one another during the interval that the composite tone continues to be heard. In many, if not all, of the composite tones heretofore produced by the sounding boards of pianos the fundamental does not at all times have greater intensity than any other partial tone of the composite tone, and the fundamental and other partial tones of the composite tone do not continue with the same relative intensity to one another during the interval that the composite tone continues to be heard, but on the contrary the fundamental diminishes in intensity and dies out much more quickly than the overtones. This is particularly noticeable in the middle and the upper part of the scale. Furthermore, the fundamental as well as each of the other partial tones, at certain periods, either stops entirely for a short time or is much weaker in intensity.

It is, of course, desirable to approach this best tone quality hereinabove defined as closely as possible, and the principal objects of my invention are (1) to produce a piano in which the strings will originate and the sounding board reproduce composite tones in which the low partial tones viz, the fundamental and first overtone will, at all times, have greater intensity than any other partial tone of the composite tone, (2) to produce such tones in which the partial tones gradually diminish in intensity as they rise in series from the fundamental or first overtone, and (3) to produce such composite tones in which the partial tones continue in regular and unbroken periodic sequence during the interval that the composite tone continues to be heard and without any intermittence in the relative intensity of the sound waves comprising the tone. Tones having some or all of such

characteristics will be of more pleasing quality.

Another object of my invention is to cause the production of a sounding board which will be sufficiently sensitive to proportionately and with substantial accuracy reproduce substantially all the vibrations that are transmitted to it from the strings through the bridges. Such a sounding board should be sufficiently thin to accurately respond to the fundamental and first overtone which I shall hereinafter call "low partial tones"; it should be of substantially uniform thickness and without ribs and should also be of substantially counterpoised texture. A board having these characteristics is more responsive to such low partial tones than the sounding boards heretofore employed as the various elements common to other sounding boards and which are eliminated, cause interference with responsiveness to and production of the low partial tones. Such a sounding board will reenforce composite tones having the low partial tones of relatively stronger intensity than any of the higher overtones and I shall hereinafter term such a sensitive board as a "predominant low partial tone sounding board" and a board which is not so sensitive as a "predominant higher overtone sounding board."

In the preferred embodiment of my invention I employ such a predominant low partial tone sounding board in combination with a support consisting of sound posts and a secondary sounding board spaced from the primary board and connected thereto by such sound posts.

Another object of my invention is to provide between the primary and secondary sounding boards a resonance cavity of a shape which will concentrate and further reinforce the tones produced by the adjacent sides of the board and particularly the fundamental and lower overtones of the composite tones.

Another object of my invention is to so position the sound posts between the boards as to cause such sound posts to cause that portion of the sound board between the bridge and the connection of such board to the frame at the opposite side of the posts to act as a lever in the transmission of vibrations from the primary board to the second-

ary board and in the transmission back to the primary board of the responding impulse caused by the resilience of the secondary board.

5 In the accompanying drawings like characters of reference denote corresponding parts throughout all the views, of which:—

Fig. 1 is a vertical transverse section of a piano embodying my invention;

10 Fig. 2 is a front elevation of a primary sounding board with a string-supporting plate and strings mounted adjacent thereto and showing in dotted lines the positions of the sound posts, and frame uprights and the 15 shape of the resonance cavity;

Fig. 3 is an elevation with the back removed and part of the frame members being shown in section;

Fig. 4 is a section on the line 4—4 of Fig. 3; 20 Fig. 5 is a vertical section through the sounding board of my piano.

Fig. 6 is a view in plan of a sound board preferably employed by me, a part of the top layer being broken away to show the cross 25 graining of the two layers;

Fig. 7 is an enlarged view of the upper corner of a modified form of sounding board and a modified bridge for the high treble strings;

30 Fig. 8 is a section on the line 8—8 of Fig. 7;

Fig. 9 is an enlarged section on the line 9—9 of Fig. 8.

Referring now to these drawings, my invention is here shown applied to an upright piano but, by suitable modifications in the frame and other parts, may be applied to grand pianos or other types. In these drawings, 1 indicates a primary sounding board 35 mounted at one side of a frame comprising end uprights 2 and 3; intermediate uprights 4, 5, and 6 and wrest plank 7 and bottom beam 8. Said primary sounding board comprises what I shall term "a predominant low 40 partial tone board" by which term I desire to include all boards or sounding elements which are adapted to segment favorably for the production or reinforcement of composite tones in which the fundamental or the first 45 overtone predominates with the higher overtones diminished in intensity in contradistinction to boards or elements which segment favorably for the production of composite tones having a predominance of higher overtones.

50 Such a sensitive sounding board must be comparatively thin and the degree of thinness is determined by the requirement that the sounding board must also be rigid enough 55 to retain its proper position when subjected to the pressure of the strings upon the bridges and to react quickly to the impulses it receives.

Practice has shown that boards of spruce 60 such as usually employed of appreciably

over one-half inch in thickness segment favorably for the production of tones having a predominance of higher overtones, and may be called "predominant overtone boards" 70 while boards of such wood of less thickness segment favorably for the production of composite tones having a predominance of fundamental or the first overtone and may be thus called predominant low partial tone boards. 75

Applicant employs a predominant low partial tone sounding board which is not reinforced by ribs attached to it. I have built up a sounding board less than the required one-half an inch in thickness from laminations or 80 superposed layers of spruce wood having the grains of each layer crossing each other at proper angles, that is 90% if two layers, 60% if three layers, etc., and have crowned the same at the time of securing such laminations together. This produces a board which is sufficiently sensitive to accurately and proportionately reproduce all the partial tones, especially the lower partial tones, and is substantially counterpoised in its fibrous texture for it has substantially the same elasticity, rigidity and tensile strength in all directions on its surface and unmounted is substantially uniformly sensitive at all points of its 85 surface. Such a sounding board would not, 90 however, in itself be rigid enough to support the pressure of the high tension strings against the bridges.

Such a "predominant low partial tone sounding board" when made of wood such as 100 spruce would not, however, have in itself sufficient rigidity and resistance to support the pressure of high-tension strings against the bridge, and requires a support which will not, first, interfere with the proper and symmetrical segmentation of the board as do the ribs hereinabove referred to and, second, which will not so decrease the sensitiveness of the board to the large segmentation as to produce a "predominant overtone board". I have 110 overcome these difficulties, by providing for such a board what I shall term "a vibrating support". 105

In the preferred embodiment of my invention, I employ such a "predominant low partial tone board" in combination with a support consisting of a secondary sounding board 9 spaced from the primary board and connected thereto preferably by a plurality of 115 suitably-disposed sound posts 10, 11 and 12. 120

I connect this secondary sounding board to the primary sounding board by such sound posts preferably at a plurality of points just below the bridges and between the same and the edge of the sounding board, two or more 125 of such sound posts preferably being employed, as shown, adjacent to the long bridge 13 and one adjacent to the short bass bridge 14.

The string-plate 15 may be mounted in the 130

conventional manner at one side of the primary board and the strings 16 extend across the bridges 13 and 14 in the usual way to cause vibrations of the strings to be transmitted to the sounding board, any suitable means being employed to vibrate the strings. The positions of the sound posts 10, 11 and 12 as hereinabove described not only supports the primary board and enables it to withstand the high pressure of the strings, but causes any vibrations transmitted by a string through the bridge of the primary sounding board to be communicated by the sound posts to the secondary board 9 which, as shown, is mounted at the outer side of marginal boards 17, 18, 19 and 20 which form a frame therefore and are preferably provided with a depressed seat 21 for the said board which, as shown, is secured at its marginal edges to its seat by strips 22 and screws 23 but may be so secured in any suitable manner. When so arranged, it completely closes the back of the piano and is spaced somewhat from the intermediate posts 4, 5 and 6 to permit free vibration intermediate its edges.

The transmission of vibrations to said secondary board 9 greatly enlarges the vibrating surface and increases the volume of sound produced by the piano, and the novel positions of such posts cause that portion of the sounding board 1 extending from the bridge to its attachment with the frame together with a post to act, in the transmission of such vibrations to the secondary sounding-board, as a composite lever with power exerted on the portion of the primary sounding-board 1 to which the bridge is connected, the fulcrum of the said composite lever being at the point of attachment of the sounding board with the frame.

The secondary sounding board 9, which also is a predominant fundamental sounding board of similar homogeneous texture is preferably left uncrowned and is arranged to cause a return or responsive resilient pressure through the sound posts to the primary board 1. In this way, any vibration of the strings will be communicated through the bridge to the primary sounding board 1, and in communicating this vibration to the secondary board, the primary board will, as aforesaid because of such positions of the sound posts, the portion of the sounding board 1 extending from the bridge to the attachment of the said sounding-board with the frame together with a post will act as a composite lever with power exerted on the portion of said primary board to which the bridge is connected, the fulcrum of the composite lever being at the point of attachment of the said primary sounding-board to the frame and the said vibrations will thus be transmitted to the resilient or vibrating secondary sounding board which is in turn vibrated. Because of its elasticity, the secondary sounding-board

gives a counter-impulse or opposite impulse and thereby not only causes a quicker recovery of the primary sounding board from the impulse of any particular vibration of a string, but causes an accelerated swing or vibration in the opposite direction, thus increasing the amplitude of vibration of the boards and the volume of sound produced thereby.

The employment of a secondary sounding board suitably spaced as above set forth from the primary sounding board also forms intermediate such primary sounding board and the secondary sounding board a resonance cavity 24 which further reinforces the tones which are produced by the primary and secondary sounding boards at the adjacent sides of such boards. To procure the most effective use of the resonance cavity so provided, I preferably have the spaces between the two boards completely enclosed except at the top of the piano which is left open to permit the discharge of the reinforced air waves therefrom. I also preferably shape the said cavity as far as possible to concentrate the sound waves produced in such cavity near a restricted outlet 25. For this purpose of concentrating air waves near the outlet, I provide each corner of the bottom of the piano with a block 26 having its inner surface 27 or 28 which forms the boundary of the cavity curved from end to end. These blocks 26 fill in and round out the lower corners and such blocks, as well as side edges of the cavity, are preferably provided with a depressed groove 29 of semi-circular cross-section for the purpose of further concentrating air waves. The side walls of the cavity intermediate the outlet and the lower end thereof are also preferably provided with blocks 30, 31, 32 and 33 having curved inwardly extending faces which project into the cavity, and are adapted to restrict the outlet and further concentrate contiguous to the outlet the air waves issuing therefrom. The intermediate posts which extend through the cavity 24 are preferably rounded off at their corners, as shown in Fig. 4, so as to present as little interference as possible to the reinforcement, conducting and concentration of sound waves by the said resonance cavity and the square inner tops of the corner posts are also preferably rounded off as shown at 24^a in Fig. 3. The intermediate posts are, as aforesaid, disposed centrally in the cavity and without touching either of the two sound boards on opposite sides thereof so that the sound waves produced in the cavity, are reinforced and concentrated and then discharged upwardly between the intermediate posts and between such intermediate posts and the end posts, an outlet or opening 25 being provided for this purpose. This outlet is preferably provided with a suitable cover 34 which may be hinged at its rear end, as shown, and preferably has

a sound channel 35 to enable the conduction of sound waves to the front of the piano. I also preferably provide in this cover at the front edge thereof, a series of discharge openings 36 to permit the discharge of air waves from the cavity therethrough when the cover is in closed position.

In Figs. 7 and 8, I have shown a slightly modified form of sounding board in which the sensitiveness of the primary sounding board is increased at the corner thereof on which the high treble strings are mounted by providing slots 37 and also by raising the end of the bridge 38 which supports the high treble strings and raising and thinning the same progressively toward the higher tones, thus enabling the highest tones to have the benefit of the greatest leverage of the bridge in the transmission of their vibrations to the sounding board 1 and still balancing the gradually reduced pressure of the strings.

Having described my invention, I claim:

1. A sounding board for pianos having a ribless rear surface and of a thinness and rigidity to segment for the reproduction of composite tones having a predominance of low partial tones, a support for the edges of said board, an additional elastic support arranged at the rear of said board and means for connecting said support and board distant from the edges thereof.

2. A sounding board for pianos of substantially counterpoised texture having a substantially smooth and ribless rear surface and of a thinness and rigidity to segment for the reproduction of composite tones having a predominance of low partial tones, a support for the edges of said board, an additional elastic support arranged at the rear of said board and means for connecting said support and board distant from the edges thereof.

3. A sounding board for pianos of substantially homogeneous texture, having a substantially smooth and ribless rear surface and composed of a plurality of superposed layers of wood, said board being of a thinness and rigidity to segment for the reproduction of composite tones having a predominance of low partial tones, a support for the edges of said board, an additional elastic support arranged at the rear of said board and means for connecting said support and board distant from the edges thereof.

4. A sounding board for pianos of substantially counterpoised texture and having a substantially smooth and ribless rear surface and composed of superposed layers of wood having the grains of such layers crossing each other, said board being of a thinness and rigidity to segment for the reproduction of composite tones having a predominance of low partial tones, a support for the edges of said board, an additional elastic support arranged at the rear of said board and means

for connecting said support and board distant from the edges thereof.

5. In a piano, the combination with strings and means for supporting and vibrating the same, of a sounding board of substantially counterpoised texture and having a substantially smooth and ribless rear surface, comprising superposed layers of wood having the grains of such layers crossing each other, said board being of a thinness and rigidity to segment for the reproduction of composite tones having a predominance of low partial tones, means for transmitting the vibrations of the strings to the board, suitable means for supporting said board at its edges, an additional elastic support arranged at the rear of said board and a plurality of posts connecting said rear surface between the edges of said board with said elastic support.

6. In a piano, the combination with strings and means for supporting and vibrating the same, of a sounding board having a substantially smooth, ribless rear surface secured at its marginal edges, said sounding board being of a thinness and rigidity to segment for the reproduction of composite tones having a predominance of low partial tones, means for transmitting the vibrations of the strings to the said sounding board, means for supporting said board at its edges, an additional elastic support arranged at the rear of said board and a plurality of posts connecting said rear surface between the edges of said board with said elastic support.

7. In a piano, the combination with strings and means for supporting and vibrating the same, of a primary sounding board comprising a sounding board having a substantially smooth and ribless rear surface and of a thinness and rigidity to segment for the reproduction of composite tones having a predominance of low partial tones; means for transmitting the vibrations of the strings to the said sounding board; means for supporting said primary sounding board at its edges, an elastic secondary sounding board independently supported at the rear of said primary board and spaced therefrom and sound posts connecting said secondary sounding board and said primary sounding board to support the latter.

8. In a piano, the combination with strings and means for supporting and vibrating the same, of a primary sounding board comprising a sounding board having a substantially smooth and ribless rear surface and of a thinness and rigidity to segment for the reproduction of composite tones having a predominance of low partial tones; a bridge for transmitting the vibrations of the strings to the said sounding board; means for supporting said primary sounding board at its edges, an elastic secondary sounding board independently supported at the rear of said primary

board and spaced therefrom, and sound posts connecting said secondary sounding board and said primary sounding board to support the latter, said posts being positioned adjacent to the bridge at the side thereof opposite to the vibrated portion of the strings.

9. In a piano, the combination with strings and means for supporting and vibrating the same, of a primary sounding board having a substantially smooth and ribless rear surface, and of a thinness and rigidity to segment for the reproduction of composite tones having a predominance of low partial tones; means for transmitting the vibrations of the strings to the said primary sounding board, means for suitably supporting said primary board; an elastic secondary sounding board independently supported at the rear of said primary sounding board and arranged to form a closure for the rear of the piano spaced from the primary sounding board to provide a resonance cavity between such primary sounding board and said closure; said cavity having walls shaped to concentrate air waves near an outlet at one end thereof and sound posts arranged between the edges of said primary and secondary boards.

10. In a piano, the combination with strings and means for supporting and vibrating the same, of a primary sounding board of substantially counterpoised texture and composed of superposed layers with the grain crossing, said primary sounding board having a substantially smooth and ribless rear surface and being of a thinness and rigidity to segment for the reproduction of composite tones having a predominance of low partial tones; means for transmitting the vibrations of the strings to the said sounding board, means for suitably supporting said board; an elastic secondary sounding board independently supported at the rear of said primary sounding board and arranged to form a closure for the rear of the piano spaced from the primary sounding board to provide a resonance cavity between such primary sounding board and closure, said cavity having walls shaped to concentrate air waves near a restricted outlet at the top thereof, and sound posts arranged between the edges of said primary and secondary boards.

11. In a piano, the combination with strings and means for supporting and vibrating the

same, of a primary sounding board of substantially counterpoised texture and having a substantially smooth and ribless rear surface and of a thinness and rigidity to segment for the reproduction of composite tones having a predominance of low partial tones; means for transmitting the vibrations of the strings to the board, means for suitably supporting said board at its edges; an elastic secondary sounding board independently supported at the rear of said primary sounding board and being of substantially homogeneous texture and of a thinness and rigidity adapted to segment favorably for the reproduction of composite tones having a predominance of low partial tones, said secondary board being arranged to close the rear of the piano to provide a resonance cavity between such primary sounding board and such secondary board and sound posts between said primary and secondary boards for vibratably supporting said primary sounding board between its edges and transmitting vibrations between the two boards.

12. In a piano, the combination with strings and means for supporting and vibrating the same, of a primary sounding board composed of superposed cross-grained layers and of a substantially counterpoised texture and having a substantially smooth and ribless rear surface and being of a thinness and rigidity to segment for the reproduction of composite tones having a predominance of low partial tones; means for transmitting the vibrations of the strings to the board, means for suitably supporting said board at its edges, means for supporting said primary sounding board intermediate its edges and spaced therefrom, comprising an elastic secondary sounding board independently supported at the rear of said primary sounding board and composed of superposed cross-grained layers and of substantially homogeneous texture and of a thinness and rigidity adapted to segment favorably for the reproduction of composite tones having a predominance of low partial tones and sound posts suitably disposed intermediate said primary and secondary boards.

In witness whereof, I have signed my name to the foregoing specification.

FLOYD S. MUCKEY.
